UNITED STATES PATENT OFFICE.

GEORGINE S. MONROSE, OF TAMPA, FLORIDA.

BRASSIÈRE.

Application filed May 2, 1923. Serial No. 636,117.

To all whom it may concern:

Be it known that GEORGINE S. MONROSE, a citizen of the United States, residing at Tampa, in the county of Hillsborough and State of Florida, has invented certain new and useful Improvements in Brassières, of which the following is a specification.

My invention relates to apparel and more particularly to the type of garments known 10 as brassières, camisoles and bust confiners.

An object of my invention is to provide a form-fitting garment having certain means for shaping and conforming the garment to the wearer's body whereby all surplus flesh 15 is comfortably and properly supported adjacent the top of the garment.

Another object of my invention is the provision of means for supporting, securing and adjusting the garment on the wearer's 20 body in a positive, secure and easily manipulated manner.

Other objects of my invention will be evident from the following specification taken in conjunction with the accompanying drawings, wherein like reference characters 25 designate similar parts:—

Figure 1 is a front perspective view of the garment in position on the wearer's body.

Fig. 2 is a front view detached from the body.

Fig. 3 is a rear view of the garment shown in Fig. 2.

Fig. 4 is a side view of a section of the 35 garment.

Fig. 5 is a sectional view taken on line 5—5 of Fig. 2.

Fig. 6 is a front perspective view of a modified form of the garment.

Fig. 7 is a perspective view of the garment shown in Fig. 6, laid out flat, and

Fig. 8 is a sectional view taken on line 8—8 of Fig. 7.

In the drawings the numeral 1 designates 45 a brassière, camisole or similar garment, comprising two similar sections, 2 and 3, each section consisting of a front body covering portion 4, a side body covering portion 5 and a rear body covering portion 6. In 50 the diaphragm portion adjacent the lower edge of each front covering portion 4 are positioned a plurality of spaced-apart, horizontally extending eyelets 7 and adjacent the rear edge of the portion 6 are positioned 55 a plurality of vertically extending eyelets

8. The front edge of each portion 4, approximately midway between the upper and lower edges thereof, is darted or cut out at 9 and the sides of the cut portion subsequently stitched together, as is indicated 60 at 10. The upper edge of each garment section 2 and 3 is provided with a curved armpit engaging portion 11, terminating in upstanding front and rear substantially pointed portions 12 and 13 adapted to be 65 positioned immediately in front and rear of the wearer's armpits and slightly above the same. Each of the substantially pointed portions 12 and 13 is provided with eyelets 14. 70

The front edges of the portions 4 of the garment sections 2 and 3 are shown vertically connected to each other by a row of stitches 15, although it will be understood that the sections 2 and 3 may be formed 75 integral at this point. The vertical rear edges of the garment sections 6 are detachably and adjustably connected to each other by single continuous lace or draw string 30, slidably threaded through the eyelets 8 80 from the top of the garment to a point adjacent the bottom thereof, where it extends outwardly in different directions to form double strand ends 16 and 17 providing loop portions 18. Slidably carried on each of 85 said strands 16 and 17 are hooks 19 having loop portions 31 adapted to engage the loop portions 18 of said strands and serving to securely hold the garment in adjusted position on the wearer's body when engaged 90 in the eyelets 7, as is clearly shown in the drawings.

It will be understood that the lacings or drawstrings 30 may be formed continuous by permanently uniting the ends of the 95 strands where they reenter the eyelets at the bottom of the vertical row of eyelets 8. I prefer however to provide an additional adjustment at this point by tying the free ends of the strands on the inner side of the garment, as will be readily understood. 100

Extending across the diaphragm portion of the front body covering portion 4 and in back of the eyelets 7 is a strip of fabric 20 suitably secured to the garment to form 105 a pocket and backing for the eyelets 7 and hooks 19 in use.

The garment is supported from the wearer's shoulders by means of detachable shoulder straps 21, each of the ends of which 110

are provided with hooks 22 adapted to engage in the eyelets 14 in the substantially pointed portions 12 and 13 of the body sections 2 and 3.

5 Between the rear vertical edges of the section 6 and the vertical row of eyelets 8 are positioned vertically extending stiffening means 23.

The modification shown in Figures 6 and 10 7 differ from the garment already described in that the front edges of the front portions 4 of the garment sections 2 and 3 are detachably connected to each other by a vertical row of fastening means such as hooks 15 and eyes 25 and stiffening means 26, such as bone, are suitably secured and arranged throughout the garment where more rigid supporting means is desired. In the modification the darts or pleats 10 are omitted.

10 Although I have shown and described a preferred construction and modification of

my invention for accomplishing the objects heretofore enumerated, it will be understood that various other modifications may be made therein by those skilled in the art 25 without departing from the spirit of my invention, as defined in the following claim.

What I claim is:

A brassière adapted to envelope the wearer's body and comprising a plurality 30 of portions having a front reinforced diaphragm portion, a series of horizontally spaced securing means on said diaphragm portion, and rear complementary vertical edges detachably and adjustably connected 35 by lacing means adapted to extend around said brassière and detachably and adjustably engage said securing means on said diaphragm portion.

In testimony whereof I affix my signature. 40

GEORGINE S. MONROSE.
